UNITED STATES PATENT OFFICE.

JAMES H. BUTLER, OF COLUMBIA HEIGHTS, ILLINOIS, ASSIGNOR TO
JOSEPH G. EBERSOLE, OF CINCINNATI, OHIO.

PIANO-ACTION.

SPECIFICATION forming part of Letters Patent No. 593,552, dated November 9, 1897.

Application filed March 22, 1897. Serial No. 628,698. (No model.)

To all whom it may concern:

Be it known that I, JAMES H. BUTLER, a citizen of the United States, residing at Columbia Heights, in the county of Cook and 5 State of Illinois, have invented certain new and useful Improvements in Piano-Actions, of which the following is a specification.

This invention relates to improvements in that part of a piano known as the "action," 10 and has for its object to provide a simple and improved device or mechanism which may be so adjusted as to prevent the hammers striking the strings when the performer is practicing on the keys, thus rendering the 15 instrument noiseless, but permitting the keys to be depressed, and allowing the performer to familiarize himself therewith, and which will furthermore possess advantages in point of inexpensiveness and durability in construction, ease of operation, and general efficiency.

To this end the invention consists in certain novel features of construction and combination of parts, as will be hereinafter described, and pointed out in the claims.

In order to enable others skilled in the art to which my invention pertains to make and use the same, I will now proceed to describe it, referring to the accompanying drawings, 30 in which—

Figure 1 is a view, partly in section and partly in elevation, of an ordinary piano-action for upright pianos, showing my improvement combined therewith and illustrating by dotted lines the position the parts will occupy when my improvement is in use. Fig. 2 is a view in elevation of a portion of the hammer and check rails and a part of the controlling-rod. Fig. 3 is a detail view illustrating a 35 modification in the manner of operating the controlling-rod. Fig. 4 is a detail view of a pedal to be used with said modification and showing a portion of the piano-casing. Fig. 5 is a fragmental view of a portion of the piano-casing, showing a slot therein for the 40 operation of the pedal; and Fig. 6 is a fragmental sectional view showing a modified manner of supporting the check-rail.

In the drawings I have illustrated an ordinary piano-action, such as is used in upright pianos, and as its construction and operation

are well known I shall refer only to such parts and the operation thereof as will be necessary to the full and clear understanding of my improvement.

55

A represents one of the key-blocks, which, as usual, is located at the end of the keyboard (not shown) and is provided with a vertical slot *a*, in which is fulcrumed a hand-lever *A'*, to the lower end of which is pivotally secured 60 one end of a sliding bar *B*, which lies and is supported horizontally below the keys *C* and is formed or provided at its inner end with an enlargement *B'*, having a forwardly beveled or inclined portion *b*, which contacts 65 with the lower end of the controlling-rod.

The controlling-rod *D* is supported in an upright position by means of brackets *d*, secured on suitable rails *d'* and *d''* within the casing of the piano. Each of these brackets 70 is provided with an opening through which the controlling-rod *D* passes to allow it a free vertical movement. As shown in Fig. 1 of the drawings, the lower end of the controlling-rod *D* normally rests on the upper surface 75 of the enlargement *B'* of the sliding bar *B*, and its upper end engages a catch or arm *c* on the check-rail *E*, which is secured to the lower portion of the hammer-rail *F* by means of hinges *e*, located at suitable distances apart between said rails. Interposed between the check-rail and hammer-rail is a spring *e'* under a twisted tension and whose ends are secured to each of said rails, respectively, (see Fig. 2,) and has a tendency 80 to force and hold the check-rail in a lowered position, as shown by dotted lines in Fig. 1 of the drawings.

In Fig. 3 I have shown a modification in the construction used for operating the controlling-rod *D*, which consists in pivotally securing to the casing of the piano below the keyboard a lever *g*, whose inner end contacts with the lower end of the rod *D* and whose outer portion is normally depressed by means 90 of a spring *g'*, secured to the piano-casing. To the outer end of the lever *g* is pivotally secured a bar or rod *g''*, whose lower end is pivotally connected to a pedal *G*, which extends through a slot *h* in the casing *H* of the 95 piano. This slot, as shown in Fig. 5 of the drawings, is provided in its lower part with 100

a shoulder h' , against which the pedal G may rest when it is desired to retain the controlling-rod in a lowered position and to prevent the hammer I from striking the strings I'.

5 In Fig. 6 of the drawings I have shown a portion of the brackets M, on the upper end of which the hammer-rail F rests and to which is pivotally secured in its upper part by means of pins m the check-rail E, which is provided, as before, on one of its ends with a catch c to engage the controlling-rod D and which when in its lowered position, as shown by dotted lines in Fig. 6, will occupy a position to restrict the movement of the back-catcher.

15 In operation my device is simple and as follows: When it is desired to prevent the hammers striking the strings, or, in other words, to throw the action out of gear, the hand-lever may be placed to the position shown by dotted lines in Fig. 1, which will force the enlargement B' on the sliding bar B rearwardly and from under the lower end of the controlling-rod D, which rod will be gradually lowered by reason of the inclined portion b of the enlargement B', and as the catch c on the check-rail E rests on the top of said rod and the said rail is under the tension of the spring e' it will be held in a lowered position, as shown by dotted lines in the last-named figure, when the back-catcher i on the knuckle i' will strike the felt strip e² thereon, thus allowing the hammer I and its shank i² to assume the position shown by dotted lines in Fig. 1, which, as will be observed, is quite a distance from the strings. In using the modification shown in Figs. 3 and 4 of the drawings, it is only necessary to depress the outer end of the pedal G until it is secured under the shoulder h' of the slot h in the piano-casing, which operation will force the bar g² upward and the inner end of the lever g downward, thus permitting the descent of the controlling-rod D, which rests on the inner end of said lever, and at the same time allowing the check-rail E to drop and be held down by means of the spring e', which, as before stated, is placed between said rail and the hammer-rail. In order to again permit the parts of the action to operate so as to strike the strings, the hand-lever A' may be placed to the position shown by continuous lines in Fig. 1, which will cause the control-

ling-rod D to rise on the inclined portion b of the enlargement B' and lift the catch c and the check-rail E, so as to be out of reach of the back-catcher i on the knuckle i' on the hammer-shank. When the modification is used, the pedal G may be released from the shoulder h' and allowed to rise upwardly in the slot h , which operation, through the medium of the bar g² and lever g, will cause the controlling-rod to be lifted, and thereby raise the check-rail.

Having thus fully described my invention, 65 what I claim as new, and desire to secure by Letters Patent, is—

1. In a piano-action the combination with a vertically-movable controlling-rod, having means to lift and lower the same, of a hammer-rail, a check-rail hinged to the hammer-rail and a catch on said check-rail engaging the upper part of the controlling-rod, substantially as described. 70

2. In a piano-action the combination with a vertically-movable rod, having means to lift and lower the same, of a hammer-rail, a check-rail hinged to the hammer-rail, a catch on said check-rail engaging the upper part of the controlling-rod, and a spring secured to the hammer-rail and check-rail and adapted to force and hold the latter-named rail in a lowered position, substantially as described. 75

3. In a piano-action the combination of a vertically-movable controlling-rod, with a hammer-rail, a spring-actuated check-rail hinged to the hammer-rail, a catch on the check-rail engaging the upper portion of the controlling-rod, a sliding bar having an inclined and enlarged portion to contact with the lower end of the controlling-rod, and a hand-lever suitably fulcrumed and connected to the outer end of the sliding bar, substantially as described. 85

4. In a piano-action the combination with a vertically-movable controlling-rod, having means to lift and lower the same, a check-rail pivotally secured and supported at a point to restrict, when in a lowered position, the movement of the back-catcher, and a catch on said check-rail engaging the upper part of the controlling-rod, substantially as described. 95

JAMES H. BUTLER.
